UNITED STATES PATENT OFFICE.

HARRY H. KERN, OF CORNELL, WISCONSIN.

GAME OF PASS.

Application filed May 8, 1924. Serial No. 711,475.

To all whom it may concern:

Be it known that I, HARRY H. KERN, a citizen of the United States, residing at Cornell, in the county of Chippewa and 5 State of Wisconsin, have invented a new and useful Game of Pass, of which the following is a specification.

The object of my invention is to provide a novel and interesting balancing game requiring a considerable degree of skill and 10 patience on the part of the player; and to provide the novel game board disclosed in the accompanying drawings, in which:—

Figure 1 is a top plan view of the game 15 board;

Fig. 2 is a section on line 2—2 of Fig. 1; Fig. 3 is a section on line 3—3 of Fig. 1;

Fig. 4 is a top plan of a modified form 20 of game board.

Fig. 5 is a section on line 5—5 of Fig. 4; Fig. 6 is a detail sectional view on line 25 6—6 of Fig. 4; and

Fig. 7 is a plan view of a modification of the gameboard.

Like numerals designate like parts in 30 each of the several views.

Referring to the accompanying drawings, I provide the game board 1 having a sinuous groove or channel 2 provided with a 35 plurality of terminals 3, each of which has a slight depression 4. I provide a number of balls corresponding with the number of terminals, the balls being differently colored to match the color of the portion of the

groove in which they are originally placed, and in the preferred form of my invention the two balls 18 and 19 are used as shown. The groove 2 consists of bends or corners 5 opening out of the terminals and having 35

opposite small recesses or bays 6, then the groove continuing in courses 14, then continuing in bends or corners 7 having opposite recesses or bays 8, and continuing in courses 15, then opening into the bends or 40

corners 9 which have opposite recesses or bays 10, then continuing in courses 16, and then terminating in the bends or corners 11 having opposite recesses or bays 12, and then continuing in the courses 17 which open 45

into the large central "pass" groove portion 13. (Or in the form shown in Fig. 7, groove 2 terminates in passage 20.) The central large groove portion 13 is of a different color from the two groove portions on either 50

side thereof; and said groove portions in turn are different from each other in color. 55

The groove 2 in its main portions or courses is of a suitable width and depth to allow a small ball of suitable diameter to run freely in it. The bends or corners of 60 this groove are preferably semi-circular, as shown in the drawings.

When the game has only two terminals, as shown in the accompanying drawings, two small balls 18 and 19 are used to play 65 it. (More balls are added if there are more terminals, as in Fig. 7.) To illustrate the method of playing the game, one of the balls, which may for example be colored red, is placed in the terminal having a different 70 color, while the other ball is placed in the opposite terminal. After thus having placed the balls in their opposite terminals, the gameboard is tilted until by properly and skillfully balancing the board the balls 75 may be rolled from their respective corners to the central enlargement 13 and there made to pass each other, and thence to go on to their respective home terminals.

At first glance, the problem of bringing 80 the little balls home to their respective terminals may seem to be an easy one, but after a trial the player finds out that this is not the case. In starting the game it is impossible to start both balls running simultaneously.

To start the game, for instance, the red ball 85 18 from the blue terminal 3, one would have to tip the gameboard slightly towards the corner marked B, and then toward the corner marked A. While these movements are 90 necessary to start the red ball from the blue terminal, they will positively prevent the blue ball, resting at the red terminal, from getting a start. The blue ball, however, will get started as soon as we tip the gameboard 95 towards the corner C, in order to make the red ball take the course 14. Following up on the movement of the red ball, and in order to make it pass round the bend 7, one must tip the gameboard in the direction of corner 100 A, and then toward corner B. While these movements will make the red ball advance, they also would tend to make the blue ball run back to the red terminal, which of course should be prevented. In order to facilitate 105 the holding of one ball at the bend between the straight courses while the other ball advances, there are provided at the inside of the bends the small recesses or bays, 6, 8, 10 and 12, as illustrated in the drawings. These 110 little recesses or bays are a very important part of this gameboard, because without

them it would be very difficult to play the game properly.

Figures 4 and 5 illustrate a modified form of my invention having the straight courses 5 of the continuous groove arranged parallel with the edges of the board instead of diagonally thereto and with the bends or corners 5 omitted but otherwise being of similar arrangement with the form illustrated in 10 Figures 1 to 3.

What I claim is—

1. In a balancing game, the combination of a gameboard having a sinuous groove, a plurality of terminals in which said groove 15 terminates, the sinuous groove having an enlarged central portion, a plurality of courses intervening between the enlarged central portion and each of the terminals, and bends or corners connecting said courses, 20 and including bays in the bends.

2. In a balancing game, the combination of a gameboard having a sinuous groove, a plurality of terminals in which said groove terminates, the sinuous groove having an en- 25 larged central portion, a plurality of courses

intervening between the enlarged central portion and each of the terminals, and bends or corners connecting said courses, and recesses formed in between the respective courses and opposite each of the bends or 30 corners.

3. In a balancing game, the combination of a gameboard having a sinuous groove, said groove terminating in oppositely positioned terminals, each of said terminals having a slight depression to receive and releasably hold balls, the groove having an enlarged central portion, the groove also having a plurality of courses and a plurality of bends or corners connecting the courses, and 40 having bays intervening between the courses and positioned adjacent to or opposite the bends or corners, the enlarged central portion of the groove being of one color and the portions of the groove extending on 45 either side thereof being of other and different colors, and a plurality of balls of different colors to match the colors of the grooves.

HARRY H. KERN.
